UNITED STATES PATENT OFFICE.

WILLIAM F. HUSSEY, OF WATERVILLE, MAINE, ASSIGNOR TO WATERVILLE IRON WORKS, OF WATERVILLE, MAINE, A CORPORATION OF MAINE.

PAPER-PULP SHREDDER.

Application filed January 20, 1923. Serial No. 613,852.

To all whom it may concern:

Be it known that I, WILLIAM F. HUSSEY, a citizen of the United States of America, and resident of Waterville, in the county of 5 Kennebec and State of Maine, have invented new and useful Improvements in Paper-Pulp Shredders, of which the following is a specification.

This invention pertains to mechanism useful in the manufacture of paper and relates more particularly to means for shredding paper pulp, whether wet or in the form of dry sheets, preparatory to its introduction into the beating machine of the paper making apparatus.

When wood pulp is shipped from the pulp mill to the paper manufacturer in a moist state, its disintegration for use in paper making is a comparatively easy matter, 10 but by reason of increased costs of handling and transportation it is now common for the pulp manufacturer to form the stock into thick, paper-like sheets which are then de-hydrated for shipment to the paper mill 15 in rolls or packages of convenient size. Such dry sheets, however, must be sub-divided by the paper manufacturer prior to introduction into the beating machine, but by reason of the density and toughness of 20 the dry stock great difficulty is experienced in reducing it to proper form for the action of the beaters. This is particularly true of the so-called Kraft pulp which is commonly employed in the manufacture of 25 heavy paper bags and similar articles, such Kraft pulp consisting of very long and strong fibers so that the sheets of dry pulp are exceedingly tough and resistant.

The principal object of the present invention is to provide mechanical means capable of expeditiously reducing paper stock in the form of dry sheets to a size suitable for introduction into the beating machine of paper making apparatus and to a condition 45 such that it is readily permeated by the liquid in the beating machine.

To this end the preferred mechanism comprises means for progressively feeding a sheet or sheets of the pulp material forward 50 until the advancing edge thereof rests upon and protrudes beyond the toothed or serrated edge of a fixed cutter, and a rotating cylinder provided with projected knives moving in paths lying between the respec-

tive teeth or serrations of the fixed cutter 55 and co-operating therewith to sever the material. Preferably the knives upon the cylinder are so arranged that adjacent knives engage the material successively and but a relatively small number of knives are actually in engagement with the material at any one time. This arrangement of the knives results in the separation of the projecting edge portions of the material by a shearing action such that the point of separation 60 moves transversely of the width of the sheet thereby greatly reducing the amount of power necessary to operate the machine and lessening the stress to which the parts are subjected when shredding tough and dry 65 material such as the Kraft pulp above referred to. The knives upon the cylinder are preferably arranged symmetrically with respect to the center of length of the cylinder, that is to say an equal number of knives 70 at each side of such center are operative at the same time, thus balancing the pressure upon the bearings of the cylinder and avoiding any tendency to shift the material laterally. As thus arranged the material 75 which is severed is provided with serrations along each edge so that the surface for penetration of the water in the beating machine is greatly increased over that which would be provided were the edge of the strip of severed material straight. To further increase the area of the strip along its severed edge the knives of the rotating cylinder 80 may be arranged so as to pass the teeth of the fixed cover with some clearance. Thus 85 instead of a clean cut, the material is partially torn so that the fibers are separated to some extent along the edge and the penetration of the water or other liquid in the beater to the interior of the strip of material is greatly facilitated.

The fixed cutter is preferably adjustable and the knives carried by the cylinder are also adjustable and readily replaceable when worn. The cylinder is conveniently formed from a plurality of knife carrying discs 90 securely bolted together and mounted upon a shaft turning in anti-friction bearings and the feeding devices are so constructed as to permit the feeding of different thicknesses 95 of material as well as to permit such feeding means to be made inoperative when desired. While particularly useful for shredding dry 100

sheets of pulp the machine is equally adapted for disintegrating moist pulp whether in sheets or in other form.

A preferred embodiment of the invention is disclosed by way of example in the accompanying drawings in which:—

Fig. 1 is a plan view of the apparatus;

Fig. 2 is a side elevation thereof;

Fig. 3 is a fragmentary side elevation 10 from the side opposite Fig. 2;

Fig. 4 is a fragmentary plan view of the fixed cutter;

Fig. 5 is a cross-section on the line 5—5 of Fig. 4;

Fig. 6 is a fragmentary side elevation 15 showing the fixed cutter and associated parts as illustrated in Fig. 1 but to larger scale;

Fig. 7 is a fragmentary side elevation of the cylinder, some of the knives being absent.

Fig. 8 is an elevation from the right-hand 20 end of the cylinder as viewed in Fig. 6, a part of the end plate being broken away and a portion of the first knife supporting disc being shown in section;

Fig. 9 is a composite view showing the 25 forward end of one of the cylinder knives to larger scale and in side elevation and in bottom plan view respectively; and

Fig. 10 is a fragmentary view illustrating 30 the shape of the strip of material severed from the sheet by the mechanism herein disclosed.

Referring to the drawings the numeral 1 indicates a supporting frame upon which is 35 mounted an inclined feed chute having the bottom wall 2 and the side members 3, 4, respectively. At its lower end the bottom wall 2 is recessed as indicated at 5 and within such recess is placed a fixed bed knife or 40 cutter 6. This cutter, as more clearly shown in Figs. 4, 5 and 6 consists of an elongate plate of substantially uniform thickness from end to end and so disposed in the recess 5 that its upper surface forms substantially 45 a continuation of the inclined bottom wall 2 of the chute. The lower edge of the cutter plate 6 is of serrated form having the V-shaped indentations 7 separated by the V-shaped teeth 8. The lateral edges of the 50 teeth 8 consist of cutter elements. Preferably the lower parts of the teeth 8 are backed off as indicated at 9 in Fig. 5 to provide proper clearance for the material being cut. At opposite ends the cutter plate 8 is provided 55 with projecting portions such as 10 (see Fig. 4). Brackets 11, 12 are secured at opposite sides of the frame 1, and these brackets are furnished with threaded openings for the reception of set screws 13 which 60 bear against the outer ends of the opposite projections 10 of the cutter member 6. By relatively adjusting the set screws 13 the cutter plate may be moved in a longitudinal direction for adjusting the position of the 65 teeth 8 with respect to the movable knives

hereafter described. A pair of lugs 14, 15 project from opposite sides of the frame 1 and these lugs are provided with threaded openings for the reception of set screws 16 which bear against the lower edge of the 70 end portions 10 of the cutter plate and serve for adjusting such cutter plate in a direction longitudinal of the feed chute. Other lugs 17, 18 also project from the sides of the frame 1, and these lugs are furnished with 75 set screws 19 which bear upon the upper surface of the cutter plate 6 and serve to lock the latter in adjusted position. If desired the cutter plate 6 may also be furnished with a series of spaced openings for the reception 80 of locking bolts passing up through openings in the frame, such bolts serving as additional means for holding the fixed cutter plate 6 in adjusted position.

A shaft 20 is journaled in suitable bearings in the frame 1, and this shaft is provided at one end with the drive pulley 21. A pinion 22 is secured to the shaft 20, and this pinion meshes with a gear 23 carried by a shaft 24 journaled in suitable bearings 85 in the frame 1. Upon the shaft 24 a feed roll 25 is mounted. This feed roll projects up through an opening in the lower wall 2 of the chute so that its peripheral surface projects slightly beyond the plane of such 90 inclined wall. At the opposite side of the frame 1 the shaft 20 is provided with a sprocket wheel 26. A sprocket chain 27 engages the wheel 26 and also engages a sprocket wheel 28 mounted upon a shaft 29 95 journaled in the frame 1. A pair of supporting arms 30, 31 are mounted to turn upon the shaft 29. These supporting arms are provided with journals at their free extremities for the reception of a shaft 32. This shaft is provided with a sprocket wheel 100 33 which is driven by means of a chain 34 engaging a sprocket wheel 35 fast to the shaft 29. A second feed roll 36 is secured to the shaft 32, such feed roll preferably 105 having a fluted surface and normally cooperating with the lower roll 25 for feeding sheet material downwardly along the chute. Ordinarily the weight of the roll 36 will be 110 found sufficient to provide the desired feeding pressure between the upper and lower rolls although if additional pressure were 115 found necessary such pressure could easily be secured by the provision of springs or weights tending to swing the arms 30, 31 120 downwardly about the axis of shaft 29.

A shaft 37 extends transversely across the frame 1 and this shaft is provided near opposite sides of the frame with arms 38, 39 respectively provided with rolls 40, 41 near their free extremities. These rolls are arranged respectively in the vertical planes of the arms 30 and 31 and normally contact therewith. A pair of actuating arms 42, 43 are secured to the shaft 37, and these arms 125 130

are provided with handles at their upper ends by means of which they may be manipulated. By swinging these arms downwardly the arms 30, 31 supporting the upper roll 5 are raised thus throwing the upper roll out of operative relation to the lower roll so as to facilitate the entrance of material between the rolls. Under some circumstances the operation of the feed rolls may be undesirable and may be dispensed with by manipulation of the arms 42, 43 as just described.

A bed frame 44 is secured to the frame 1 in any desired manner and this bed frame 15 is provided with oppositely disposed anti-friction journal bearings 45, 46 within which a shaft 47 is mounted to turn. The shaft 47 extends beyond the bearing 45 and constitutes a drive pulley with which a belt 48 20 engages. If desired the end of the shaft 47 may be provided with a guard disc 47^a to prevent slipping of the belt therefrom. The belt 48 passes about the periphery of the drive pulley 21 and serves to impart 25 movement thereto. This belt 48 is preferably slack and may be operatively tensioned by means of a tension pulley 49 mounted upon a shaft 50 carried by an arm 51. The arm 51 is secured to a shaft 52 30 which extends transversely across the frame 1, being mounted in bearings therein. Near opposite ends of this shaft, arms 53, 54 are secured thereto and these arms are provided with handles at their upper ends whereby 35 the shaft 52 may be turned. By turning this shaft the supporting arm 51 may be rocked, thereby lifting the tension pulley 49 from the belt 48, permitting the latter to become so slack that it ceases to drive the pulley 21 40 and the shaft 20. By thus slackening the belt the operation of the feed rolls may be stopped. The opposite end of the shaft 47 projects beyond the bearing 46 and is provided with a drive pulley 55 for the reception 45 of a belt driven from any suitable source of power.

A disc 56 (Figs. 7 and 8) is mounted upon the shaft 47 at a point just within the bearing 45. Preferably this disc is shrunk on to 50 the shaft so as to be securely fixed thereto. A series of knife carrying discs 57 of like diameter are mounted in juxtaposed relationship upon the shaft 47 and between the end disc 57 and a second end disc 58 mounted 55 upon the shaft 47 just within the bearing 46. The disc 58 is preferably secured in position by means of a nut 59 engaging a screw threaded portion of the shaft 47. By tightening this nut the several discs 57 may be 60 securely clamped together. Bolts such as 60 extend longitudinally through the several discs 57 and the end discs 56 and 58 and provide additional means for uniting the several discs into a unitary cylinder.

65 Each of the discs 57 is provided with a

plurality of recesses in its opposite faces. These recesses extend substantially parallel to tangents to the peripheral surface of the respective discs thus in effect defining chords of the disc, and are open at one end at the 70 peripheral surface of the disc. In Fig. 8 one of such recesses is indicated at 61 and the points at which such recesses open at the circumference of the disc are indicated for example at 62. These recesses preferably do 75 not form a complete chord but terminate at a point substantially in a diametral plane of the disc, but from the inner ends of each recess, an opening of small diameter, such as indicated at 62, may extend outwardly to 80 the peripheral surface of the disc. The recesses are preferably of substantially rectangular cross section as indicated in Fig. 7 and serve for the reception of knives 63. These knives are also of rectangular cross 85 section and are arranged to project beyond the peripheral surface of the disc in which they are mounted. The projecting portion of each knife is of substantial V shape as indicated in Fig. 9, providing the cutting 90 edges 64, 65. The end surfaces of the knives are preferably backed off, providing the inclined faces 66, 67 which intersect along the line 68.

Associated with each of the recesses in the several discs is a substantially radial opening such as 69 which communicates with the corresponding recess by means of a threaded bore. A set screw 71 engages the threaded bore and serves to retain the cutter in adjusted position within its respective recess. Preferably lock nuts 72 are provided for holding the respective set screws 71 in adjusted position. In the preferred arrangement, three of the recesses 61 95 are provided in each face of each disc, the several recesses in each face being spaced at equal distances circumferentially of the disc and the recesses in opposite faces alternating with one another in position. 100 These recesses are open at that side of the disc in which they are formed but the knives are prevented from escaping laterally therefrom by engagement with an un-recessed portion of the next adjacent disc. 105 The openings 62 which form extensions of the recesses are provided to permit the admission of a driving pin for removing the knives from the recesses when it is desired 110 to take them out for grinding or replacement.

As indicated in Fig. 7 the several discs 57 are so disposed that the knives 63 extend in helical series about the peripheral surface of the cylindrical support. Preferably also the discs are so arranged that the series of knives extend in opposite directions from a point substantially central of the length of the knife supporting cylinder. 120 In Fig. 7 the knives of one of such series 125 130

are indicated generally by the character 63^a while the knives of the intersecting series extending in the opposite direction are indicated at 63^b. With this arrangement a 5 relatively small number of the knives are brought into cooperative relationship with the fixed cutter plate 6 at any one time so that the power required for rotating the knife carrying cylinder is much less 10 than would be required were all the knives to act simultaneously. It is also clear that by reason of the helical arrangement of the knives the cutting action of the knives in a series is progressive so that the material 15 is severed by a shear cut. As the series of knives are disposed symmetrically with relation to the central point of the cylinder, the shearing action progresses in opposite directions from such central point 20 so there is no unbalanced face tending to move the sheet of material laterally under the action of the cutting elements.

Preferably the cylindrical support for the knives is encased in the housing comprising 25 members 73, 74 (Fig. 2) and this housing is provided with a discharge opening at 75. As the sheets of material are fed down along the lower wall 2 of the chute they are gripped by the feed rolls and moved 30 forwardly until their advancing edges project over and beyond the serrated edge of the fixed cutter 6. The knives 63 carried by the revolving cylinder describe paths defining planes which preferably substantially 35 bisect the indentations 7 in the fixed cutter, suitable clearance being provided between the knives 63 and the teeth 8. As the knives 63 pass the plane of the cutter plate they sever the projecting lower edge 40 of the sheet material from the main body of the latter thus producing strips 76 of serrated or zigzag form such as shown in Fig. 9. Preferably the fixed cutter is so adjusted that a substantial clearance is provided 45 between the teeth 8 and the moving knives so that instead of a clean cut a ragged or torn edge is formed upon the strip which is severed from the sheet material, such torn or ragged edge facilitating 50 the absorption of water during the beating operation. While such a combined cutting and tearing action is preferred it is evident that by proper setting of the knives 63 and the fixed cutter 6 a substantially 55 smooth shearing action may be obtained.

While as herein shown the teeth 8 providing the fixed cutter elements are integrally united, it is clear that they might be formed as separate members suitably secured in position, while it is also clear that the knives 63 might be supported in other manner than that herein disclosed.

I claim:

1. Apparatus for use in shredding paper stock comprising a fixed cutter having a

serrated edge, means for moving the stock to cause its advancing edge to project over the edge of the cutter, and a rotary cylinder provided with a series of knives projecting from its peripheral surface, said series extending helically along said surface, the several knives of the series co-operating successively with the serrations of the fixed cutter to remove a zig-zag strip from the main body of the stock. 75

2. Apparatus for shredding paper stock in sheet form comprising a series of fixed cutter elements collectively forming a serrated cutting edge, means for moving a sheet of the material over said elements to cause its advancing edge portion to project beyond said serrated edge, and a helical series of movable knives arranged to move along paths passing through the respective indentations of said serrated edge, said knives being arranged successively to engage the sheet of material to remove the projecting edge portion thereof by a zig-zag shear cut progressing transversely of the width of the material. 80

3. Apparatus of the class described comprising a fixed cutter having a serrated edge consisting of V-shaped teeth separated by V-shaped indentations, a helical series of movable knives having V-shaped cutting edges, and means for moving the respective knives of said series successively through successive indentations of said fixed cutter. 95

4. Apparatus of the class described comprising a fixed cutter having a serrated edge, a cylinder mounted to turn about an axis parallel to the plane of said edge, and a helical series of knives extending axially of the cylinder from its center substantially to its end and cooperable with said fixed cutter, the knives of said series being so disposed peripherally of the cylinder as successively to approach the plane of the fixed cutter when the cylinder is rotated. 100

5. Apparatus for shredding sheet material comprising a series of fixed cutter elements disposed in the same plane, a rotary cylinder turning about an axis substantially parallel to the plane of said cutter elements, and two oppositely extending helical series of spaced knife elements protruding from the peripheral surface of the cylinder and cooperating with said fixed cutter elements for severing the material by a shear cut progressing in opposite directions axially of the cylinder. 110

6. Apparatus of the class described comprising a fixed cutter and a rotary cylinder, said cylinder having two helically extending series of knives protruding from its surface, said series extending oppositely and intersecting at a point substantially midway the length of the cylinder. 115

7. Apparatus of the class described comprising a fixed cutter having a serrated edge 120

- and means cooperating therewith to produce a shear cut progressing in opposite directions from the center of said fixed cutter toward its opposite ends.
8. Apparatus for shredding paper stock comprising a fixed cutter having a serrated edge, a plurality of movable cutting elements, and means for moving said movable elements into cooperative relationship to said fixed cutter to produce a shear cut progressing in opposite directions from the center of the fixed cutter.
9. Apparatus of the class described comprising a rotating cylinder, two helically extending series of knives carried thereby, said series intersecting substantially at the center of length of the cylinder and extending symmetrically in opposite directions therefrom, and means for supporting material to be cut in position for engagement by said knives.
10. Apparatus of the class described comprising a rotary cylinder, helical series of knives mounted thereon, said series being arranged in two groups, the series of one group extending oppositely to the series of the other group, corresponding knives of the series of each group being disposed symmetrically as respects the center of length of the cylinder, and means for holding material to be cut in position for engagement by said knives.
11. Apparatus for shredding sheet material comprising a cylinder having a plurality of peripherally spaced helically extending series of knives protruding from its surface, and other and oppositely extending series of knives also protruding from the surface of the cylinder, each of said first named series intersecting one of the latter named series at a point substantially midway of the length of the cylinder.
12. A cylindrical cutter support for a paper stock shredder comprising a series of discs secured in face to face engagement, each of said discs having a recess in its face, and a knife clamped within said recess.
13. A cylindrical cutter support for a paper stock shredder comprising a series of discs each having a chord-like recess in one face thereof, a cutter seated in said recess with its operative extremity protruding peripherally from the disc, means for securing said cutter in the recess, and means securing the discs together in coaxial alignment.
14. A cylindrical cutter support comprising a series of coaxial discs each having a knife holding recess in one of its faces, and a knife seated in such recess, each disc having an opening extending from the inner end of its respective recess to its peripheral surface, said opening providing for the insertion of a tool for forcing the knife out of the recess.
15. A knife supporting cylinder for pulp shredders comprising a plurality of coaxial discs, each disc having a recess in its opposite faces for the reception of cutters, and means for securing a cutter in each recess.
16. A knife supporting cylinder for pulp shredders comprising a knife supporting disc having a plurality of recesses in each of its opposite faces, the recesses in each face being equally spaced and recesses in one face alternating with those in the other, and means for securing a knife in each of said recesses.
17. A cylindrical cutter support comprising a series of coaxial discs each having a plurality of symmetrically spaced chord-like recesses in one of its faces, a cutter seated in each recess, and means for securing each cutter within its respective recess.
18. A cylindrical cutter support for a paper stock shredder comprising a series of coaxial discs, and means for holding said discs in face to face engagement, each of said discs having an elongate recess in one face opening at its peripheral edge, a cutter seated within said recess and held against lateral escape therefrom by the next adjacent disc, and means for securing the cutter against lengthwise movement in the recess.
19. A cylindrical cutter support comprising a series of juxtaposed coaxial discs each having a recess in one face extending inwardly from its peripheral edge and closed at the face of the disc by the next adjacent disc, a cutter seated in each recess and protruding from the open end thereof, and set screws engaging threaded openings in the respective discs for holding the cutters in position therein.
20. A cylindrical cutter support for a paper stock shredder comprising a shaft having a series of juxtaposed coaxial discs mounted thereon, each of said discs having a cutter adjustably secured thereto, an end disc arranged at each end of the series, a plurality of connecting elements extending through the end discs and knife carrying discs for holding them against relative movement, and means for securing said end discs to the shaft.
21. A cylindrical cutter support for a paper stock shredder comprising a series of juxtaposed discs, knives carried by said discs, a shaft upon which the discs are fixedly mounted, means for supporting paper stock in the path of movement of said knives, and antifriction bearings for supporting opposite ends of said shaft.
22. Apparatus for shredding paper stock comprising a rotary cylinder having helically extending series of spaced knives protruding from its peripheral surface, a normally fixed cutter arranged substantially parallel to the axis of the cylinder and having elements cooperable with said knives for

cutting the paper stock, and means for adjusting the cutter in a longitudinal direction.

23. Apparatus for shredding sheet material comprising an inclined feed chute, a fixed cutter arranged at the lower end of said chute with its upper face substantially in the plane of the bottom of the chute, said cutter having a serrated cutting edge, and 10 a plurality of knives movable past the plane of the fixed cutter successively and cooperative respectively with successive serrations of said edge for severing zig-zag portions from the advancing edge of a sheet of material moving down its chute.

24. Apparatus for shredding dry paper stock in sheet form comprising a feed chute terminating in a serrated cutter, a rotating cylinder having helically extending series of knives cooperating with the serrated cutter, 20 a pair of feed rolls for moving sheet material along the feed chute toward the serrated cutter, one of said rolls being movable toward and from the other, and means for driving each of said rolls in all positions 25 thereof.

Signed by me at Waterville, Maine, this sixteenth day of January, 1923.

WILLIAM F. HUSSEY.
